(57) **CLAIM**

The ornamental design for an electric winch, as shown and described.

DESCRIPTION

FIG. 1 is a perspective view of an electric winch showing my new design;

FIG. 2 is a right side elevational view thereof;

FIG. 3 is a top plan view thereof;

FIG. 4 is a front elevational view thereof;

FIG. 5 is a bottom plan view thereof;

FIG. 6 is a left side elevational view thereof; and,

FIG. 7 is a rear elevational view thereof; and,

FIG. 8 is a perspective view of an electric winch embodying my new design, the cord and hook shown in broken lines are for illustrative purposes only and form no part of the claimed design.
